Miner P. Wetmore,
Inventor

By his Attorney
A. Parker Smith

UNITED STATES PATENT OFFICE.

MINER P. WETMORE, OF NEWARK, NEW JERSEY, ASSIGNEE TO HYGRADE ENGINEERING CO. INC., A CORPORATION OF NEW JERSEY.

STEM AND MOUNT FOR INCANDESCENT-LAMP FILAMENTS.

1,359,134.

Specification of Letters Patent. Patented Nov. 16, 1920.

Application filed July 18, 1918. Serial No. 245,442.

To all whom it may concern:

Be it known that I, MINER P. WETMORE, a citizen of the United States of America, residing at Newark, county of Essex, State 5 of New Jersey, have invented certain new and useful Improvements in Stems and Mounts for Incandescent-Lamp Filaments, of which the following is a specification.

My invention relates to incandescent 10 lamps and comprises a special form of stem and arrangement of leading-in wires for such lamps. While my invention is applicable to any form of incandescent electric lamp, its use is especially advantageous in 15 the manufacture and use of small, high powered, tungsten filament lamps such as are used for automobile headlights, and in the manufacture and use of gas filled lamps. In lamps of these classes it has been customary to weld together two kinds of wire 20 to form the conductors passing from an external source of current supply through the lamp stem, or seal, to the tungsten filament within. The inner section of each such 25 wire is usually made of nickel, the welded joint, or knot between the nickel and other sections being embedded in the glass of the seal. The inner ends of the nickel sections are usually flattened and then bent around 30 to form cups, or tube sections, into which the ends of the tungsten filament are set. Nickel is preferred for these inner sections because it is affected less than other available metals, by the heat and gaseous 35 reactions within the lamp.

The making of these welded joints and the flattening and bending of the ends of the nickel sections, are both rather delicate and costly operations, and the portion of 40 solid nickel wire embedded in the seal is apt to crack the glass of the stem by its expansion under heat,—the coefficient of expansion of nickel being much greater than that of glass. My present invention over- 45 comes all these difficulties by employing short sections of nickel tube, instead of the solid nickel wires heretofore used, and by fastening such tube to the other wire section by collapsing or pinching it on the same 50 at one or more points and then embedding the telescoped end of the nickel tube in the glass of the stem forming the seal. The best construction at present known to me, made according to my invention, is illus-

trated in the accompanying sheet of drawing in which,

Figure 1 is a side elevation of a completed (but unbased) lamp with parts broken away or shown in section, and

Fig. 2 is a cross section of the stem on the line 2—2 of Fig. 1.

Throughout the drawings like reference characters indicate like parts: 1, is the lamp bulb and 2 the glass stem, into, and through which the outer sections 3, 3, of the leading- 65 in wires are sealed. These are of some metal or alloy which have substantially the same rate of expansion under heat as the glass of stem 2. The nickel tube sections 4, 4, are collapsed, or pinched down at 5, 5, on 70 the wire sections 3, 3, telescoped into them, and also at their free ends 8, 8, on the ends of the tungsten filament 7, to which they may be welded, or cemented. Preferably the pinched or collapsed tube sections 5, 5, 75 do not extend along the entire telescoped sections of wires 3, 3, but the end portions of the tubes are left in their original circular shape, concentric with wires 3, 3, with a ring shaped space 6, between, as indicated 80 in Fig. 2.

The advantages of my invention are obvious. By the use of an automatic machine these telescoped and pinched-together leading-in wires can be rapidly and accurately 85 made from continuous lengths of wire and cold drawn tubing, at much less cost and with much less waste, than the old form of solid wire "welds" could be made. The cups for reception of the filament 7, formed 90 by the free ends of the tubes 4, 4, are much more perfect than the cups formed by flattening and rolling up the ends of a solid nickel wire, as in the old practice, and these cups when pinched down in the form shown 95 at 8, 8, make a better joint with the filament than do the flattened and curled ends of solid wires. Finally, the telescoped but unpinched ends of the nickel tubes embedded in the glass of the stem 2, while firmly held thereby and so able to exert the full benefit of the 100 stiffness of their tubular form as supports for filament 7, are hollow, and expand and contract radially less under heat than would solid wires of the same diameter with consequent less tendency to crack the seal. Furthermore, such radial expansion of 105 these thin tubes as does occur, exerts less

bursting force on the surrounding glass than would the expansion of a solid nickel wire, and may be entirely absorbed in the buckling or bending of the thin tube walls, instead of resulting in a bursting out of the glass walls of the cavities in which the tubes rest.

Various changes could be made in the details of construction and proportions of parts shown, without departing from the essence of my invention so long as the general principles of construction and operation above explained are preserved in substance.

15 Having described my invention, I claim:

An incandescent lamp stem and filament mount which comprises in combination a stem of glass, a wire section sealed into said glass, and a section of metal tube telescoped and fitting loosely over and pinched 2 on to the end of the wire at a point some distance from the end of the tube, an unpinched portion extending in one direction a short way into the glass of the seal and in the other direction beyond the end of the 25 wire to form a cup, portions of the tube circumference not pinched being spaced away slightly from the telescoped wire.

MINER P. WETMORE.
